UNITED STATES PATENT OFFICE.

WALTER B. DAHL, OF MINNEAPOLIS, MINNESOTA, ASSIGNOR, BY MESNE ASSIGNMENTS, TO B. P. KIMBALL, OF MINNEAPOLIS, MINNESOTA.

TEMPERATURE-REGULATOR.

1,096,004.

Specification of Letters Patent.

Patented May 5, 1914.

Original application filed October 25, 1912, Serial No. 727,716. Divided and this application filed January 21, 1913. Serial No. 743,259.

To all whom it may concern:

Be it known that I, WALTER B. DAHL, a citizen of the United States, residing at Minneapolis, in the county of Hennepin and 5 State of Minnesota, have invented certain new and useful Improvements in Temperature-Regulators, of which the following is a specification.

My invention relates to new and useful 10 temperature regulators, especially such regulators in which a thermostatic lamina operates to make or break an electric circuit when the temperature goes above or falls below a certain point, the said circuit controlling 15 means for opening and closing the drafts of a furnace.

This application is a division of my co-pending application, Serial Number 727,716.

It is the object of my invention to construct such a lamina in which the different 20 strips of metal forming the same are combined and held together by stamping portions of one strip into and over operations of the other strip, thus avoiding the usual welding.

It is also an object of my invention to provide means carried by the end of the lamina for adjusting the switch plate so that it will make contact at the proper moment relative 30 to the determined temperature, said adjustment being made without changing the position of the contact points, which will be definitely adjusted and fixed at the factory.

The full objects and advantages of my invention will appear in connection with the 35 detailed description thereof and are particularly pointed out in the claims.

In the drawings illustrating the application of my invention in one form, the figure 40 is a plan view of the thermostat having my inventions applied thereto.

As shown in this drawing, a base plate 10 is provided having thereon a post 11, to which is secured one end of a thermostatic 45 lamina 12 curved in a spiral of the usual form and having a radial extension 13 at its free end. The lamina 12 is formed of two sheets of metal locked together by means of tongues 14, one strip interlocking with 50 and lapping over the other strip. The

aforesaid radially extended portion 13 has secured thereto at 15 a contact strip 16 which extends between two contact points 17 and 18, which contact points are relatively fixed to a non-conducting member 19 and spaced apart a suitable distance. The radial member 13 is provided with an offset portion 21 within which is threaded a screw 22, the end of said screw bearing against contact strip 16.

It will be apparent that by turning the screw 22, the position of the contact plate 16 may be adjusted relative to contact points 17 and 18 so as to determine the temperature at which contact will be made with one or 60 the other of said contact points. The contact points 17 and 18 are rigidly secured to the plate 19 and will never need adjustment after leaving the factory, all required adjustment of contact plate 16 being effected 65 by means of the screw 22. The plate 16 is, of course, made of spring metal so that the adjustment above described is very delicate and thoroughly effective for the purpose. Such an adjustment is very desirable because 70 the distance between the contact points 17 and 18 is necessarily small, and a variation thereof may render the thermostat either inactive or wholly inoperative. It is extremely difficult to adjust the points relative to the 75 contact bar 16 without varying the distance between the points. With my device, as above stated, no variation in the distance apart of the points ever occurs since that distance is fixed at the factory. The high 80 utility and desirable characteristics of my novel adjusting device will, therefore, be 85 obvious.

I claim:

1. A temperature regulator comprising a 90 lamina secured at one end and freely movable at the other end, a pair of contacts spaced apart, a switch plate carried by the movable end of the lamina and extending between the contacts, and means connected 95 to the end engaging the switch plate at a point outside of the point of connection thereof to the lamina for adjusting the position of said switch plate relatively to the contacts.

2. A temperature regulator comprising a lamina having a rectilinear arm and an offset portion on said arm, a pair of contacts spaced apart, a switch plate riveted to the arm of the lamina and extending between the contacts, and a screw threaded into the offset portion of said arm and engaging said switch plate for adjusting the

position of the same relatively to the contacts.

In testimony whereof I affix my signature in presence of two witnesses.

WALTER B. DAHL.
